UNITED STATES PATENT OFFICE.

JOHN L. HALL, OF SCHENECTADY, NEW YORK, ASSIGNOR TO THE GENERAL ELECTRIC COMPANY, A CORPORATION OF NEW YORK.

SEARCH-LIGHT.

SPECIFICATION forming part of Letters Patent No. 726,529, dated April 28, 1903.

Application filed August 17, 1900. Serial No. 27,132. (No model.)

To all whom it may concern:

Be it known that I, JOHN L. HALL, a citizen of the United States, residing at Schenectady, in the county of Schenectady and State of New York, have invented certain new and useful Improvements in Search-Lights, (Case D, 1,801,) of which the following is a specification.

In operating search-light projectors, especially aboard ship, it is imperative at times that some means of control should be provided which admits of operation at a distance for training the projector so as to direct the beam at a desired angle as to altitude and azimuth. This is sometimes effected electrically and sometimes by means of a system of rope transmission.

My present invention relates to a system of flexible shafting between the projector and the operating-stand, which may lead from the operating-point to the projector around an intervening obstruction. For example, the projector is sometimes mounted on the forward side of a mast, while the operator who trains the projector is some distance behind the mast. I accomplish the result by the employment of a system of operating connections connected together by universal joints, provided with operating-handles at one end and with gearing at the other end by which the two movements of the drum for altitude and azimuth may be independently adjusted. The parts are connected by universal joints and are inclosed one within the other, the outer one being tubular, forming a very compact structure. Below the pedestal of the projector-drum is mounted a system of gearing, one gear-train effecting the rotation of the drum for azimuth and the other being connected by a crank with a reciprocating plunger connected by a link to the projector at a point eccentric to its pivots, thereby permitting it to be raised and lowered on its pivots to elevate or depress the beam of light.

The novel features will be more fully pointed out hereinafter, and will be definitely indicated in the claims.

In the accompanying drawings, illustrating my invention, Figure 1 is a side elevation of a system embodying my improvements. Fig. 2 is a sectional view showing the concentric

arrangement of the operating-shafting. Fig. 3 is a side elevation of the gearing controlling the movement of the drum, and Fig. 4 is a detail sectional view of the drum-operating gearing.

1 represents the drum of a search-light projector, mounted, as usual, on pivots trunnioned in the forked arms of a pedestal 2, which may be supported on any suitable frame at the pilot-house of a vessel or other location from which it is desired to manipulate the projector. Rigidly connected with the projector by means of a tubular shaft is a bevel-gear 3, by the rotation of which the drum may be revolved to any suitable angle. Capable of movement vertically within the tubular shaft is a rod 4, at the upper end of which is fixed a cross-bar on which are journaled links 5 5^a, pivoted, as indicated in Fig. 1, to the drum or a casting secured thereto at a point eccentric to its journals. The movements of the rod 4 are controlled by a crank 6, rigid with the axis of a gear-wheel 7, the end of the crank carrying a roller 8, engaging a groove in the cross-head 9, fastened to the lower end of the rod 4. The cross-head is mounted in a guide 10. The gear-wheel 7 is connected by a sprocket-chain with a pinion 11, secured to a shaft 12, the outer end of which is connected by a universal joint with the shaft 12^a and the latter by a second joint of the same kind with the shaft 12^b, leading to the point of control and provided with a hand-operating wheel 13. The shafts 12 12^a 12^b are journaled within tubular bearings secured to the ends of the tubular shafts 14 14^a 14^b, provided with a second hand-operating wheel 15. At the point of control the tubular shaft 14^b is journaled in a standard 16, provided with a threaded socket to permit it to be secured to a post or other support at the point of control, as indicated in Fig. 1 at 17. The shaft-sections are connected by universal joints which are of the same size and type and the construction of which is clearly indicated in Figs. 1 and 2. Each shaft end carries a fork the prongs of which are pivoted to a ring or disk, (see Figs. 1 and 2,) one pair of pivots being vertical and the other horizontal. The tubular shaft has its ends connected to a ring 18, in which are four set

screws the heads of which project into and form journals for the forks of the joints, as will be readily understood from a comparison of Figs. 1 and 2. The couplings are fastened 5 by pins, as indicated in Fig. 2, to the ends of the tubular shaft or to the ends of the rod inclosed within the tubular shaft. The end coupling of the tubular shaft turns in bearings in the supporting-standard 13^a, as indicated in dotted lines in Fig. 3, and carries a pinion 19, connected by a sprocket-chain with a pinion 20, driving a bevel-gear meshing with the gear 3. Thus by a movement of 10 the handle 15, which controls the tubular- 15 shaft system, the gear may be rotated more or less and the pedestal of the projector correspondingly shifted, so as to adjust the beam at any desired angle in a horizontal plane. Similarly, a movement of the handle 13 op- 20 erates the solid inner-shaft system and rotates the shaft 12, thereby operating through the sprocket-chains the gear-wheel 7 and turning the crank 6 through any desired angle, so as to tilt the projector in a vertical 25 plane. By reason of the universal joints the operating-stand may be placed at a considerable angle to the projector and the shafting may be led around an obstruction. The intermediate sections of the shafts 12^a 14^a may 30 be of any desired length, so that the operating-stand may be put at any desired point.

Having thus described my invention, what I claim as new, and desire to secure by Letters Patent of the United States, is—

35 1. Means for manipulating a search-light projector, comprising two concentric and independent shaft systems between the point of control and the projector, said shaft systems being provided with universal joints, 40 and connections of the two systems respectively with the projector for making adjustments in different planes.

2. Means for manipulating a search-light projector, comprising operating devices at the point of control for training the beam in 45 azimuth or altitude, and two shaft systems one inclosed within the other, each composed of a plurality of parts connected by universal joints.

3. Means for manipulating a search-light 50 projector, comprising gearing at the base of the projector for rotating the drum in a vertical and horizontal plane respectively, operating-handles at the point of control, and two or more systems of shafting one inclosed with- 55 in the other, each composed of several parts connected by universal joints, connecting the operating-handles to the gearing.

4. Means for manipulating a search-light 60 projector, comprising a pedestal, a drum trun- 65 nioned thereon, gearing for rotating the pedestal, a vertically-movable rod linked to the drum at a point eccentric to its axis, a crank for reciprocating the rod, two shaft systems, each formed of a plurality of concentric sec- 70 tions connected together by universal joints and acting upon gearing connecting with the rod and pedestal, and operating devices at the point of control for independently rotat- 75 ing the shafts.

5. Means for manipulating a search-light 75 projector, comprising two concentric systems of flexible shafting, connections between the drum and shaft systems for rotating the drum in a horizontal or a vertical plane, and inde- 80 pendent manipulating devices for the two systems of shafting.

In witness whereof I have hereunto set my hand this 15th day of August, A. D. 1900.

JOHN L. HALL.
